SPRAYER PUMP

Ray G. Brooks, Irving, Tex., and James C. McKinney,
Simpsonville, S.C., assignors to Morton-Norwich Products, Inc.

Filed July 1, 1974, Ser. No. 484,751

Term of patent 14 years

Int. Cl. D9—07

U.S. Cl. D9—276

FIG. 1 is a front elevational view of a sprayer pump showing our new design.

FIG. 2 is a left side elevational view.

FIG. 3 is a rear elevational view.

FIG. 4 is a right side elevational view.

FIG. 5 is a top plan view; and

FIG. 6 is a bottom plan view thereof.

We claim:

The ornamental design for a sprayer pump, as shown.
